INVENTOR:
HENRY R. HUBERICH
BY *Alfred B. Davis*
HIS ATTORNEY.

UNITED STATES PATENT OFFICE.

HENRY R. HUBERICH, OF CLEVELAND, OHIO, ASSIGNOR TO GENERAL ELECTRIC COMPANY, A CORPORATION OF NEW YORK.

ADJUSTABLE LAMP-FIXTURE.

1,269,538.

Specification of Letters Patent. Patented June 11, 1918.

Application filed August 21, 1915. Serial No. 46,626.

To all whom it may concern:

Be it known that I, HENRY R. HUBERICH, a citizen of the United States, residing at Cleveland, county of Cuyahoga, State of Ohio, have invented certain new and useful Improvements in Adjustable Lamp-Fixtures, of which the following is a specification.

My invention relates to electric lamp fixtures and more particularly to fixtures of this character which are provided with means for adjusting the light source to various positions and which are especially serviceable for reading, shaving and other operations 15 requiring an adjustable lamp.

According to my invention, I provide a standard having a slot to receive the lamp and means whereby the lamp may be clamped in various positions in said slot. 20 The lamp support which engages the slot and the clamping device are so disposed as to afford very convenient means for the insertion of the electric conductors leading to the lamp. Another feature of my invention 25 is that the standard to which the lamp is secured is adjustable with respect to the base, and to this end is provided with a slot and clamping means whereby the standard may be caused to assume a great variety of positions. By means of the combination of 30 these features a wide range of adjustability is obtained. My invention further comprises specific improvements in the attachment of the lamp to the standard, and in the 35 attachment of the standard to the base. The device as a whole presents an ornamental appearance and various other features and advantages thereof will appear from the following detailed description of a species 40 thereof and from the accompanying drawing.

In the drawing, Figure 1 is an end elevation of a portable lamp and support constituting one exemplification of my invention; Fig. 2 is a side elevation thereof showing in dotted lines one position to which the lamp and standard respectively may be moved; Fig. 3 is a detail, partly in vertical section on the line 3—3 of Fig. 1, showing the parts on an enlarged scale, and Fig. 4 is a detail showing one of the clamps and adjacent parts.

The lamp shown comprises a base 10 of suitable weight to balance the other parts 55 in any of the desired positions. An eye 11

may be attached to the said base so as to enable the device to be supported on a wall, if desired, in which case the base 10 will assume a vertical position. Ordinarily however, the base is intended to be horizontal 60 and the device to be supported upon a desk, table or similar article of furniture. Supported upon the base 10 is an adjustable standard 12, which, as shown, is S-shaped. The upper and lower curved portions 13 and 65 14 respectively of the standard are slotted substantially throughout, as shown at 15 and 16 respectively. The slot 15 permits of the adjustment of a lamp 17 carried in socket 18, and, if desired, a reflector 19. 70 The slot 16 permits the standard to be adjusted with respect to the base 10.

The attachment of the standard 12 to the base 10 is, as shown, substantially the same as that of the lamp socket 18 to the standard 75 12, except that in the former case the attachment 20 is so disposed that the member 12 is movable relatively thereto, whereas in the latter case the attachment 21 is so disposed that it is movable with respect to the 80 standard 12. Inasmuch as the clamping portions of these parts are substantially the same, the attachment 21 only is illustrated and is shown in Fig. 3. The lamp socket 18 has at the bottom thereof an internally 85 threaded sleeve 22 in which engages an externally threaded tubular bolt 23, thus providing a socket supporting means at one end of the said bolt. The tubular bolt 23 permits the passage of the conductors 24 leading 90 to the socket terminals. The said bolt passes through the slot 15 in the standard 12, having a flattened portion 25 engaging the said slot so as to prevent turning. The head 26 of the said bolt engages the inner 95 surface of the curved portion 13 of the standard 12. The bolt 23 also passes loosely through and carries bearing plate 27 which, as shown, is of a channel shape, the side members of which engage the outer surface 100 of the portion 13. The said sides have projections 28 which enter the slot 15 and serve to guide and center the bearing plate as well as the bolt 23 and attached parts with respect to the standard 12. A clamp or winged 105 nut 29 is threaded upon the bolt 23 intermediate the sleeve 22 and the bearing 27.

By loosening the clamp or winged nut 29, the bearing plate 27 and the parts carrying the same may be moved to any desired position 110

with respect to the slot 15, whereupon the clamp may be tightened, thus drawing the head 26 of bolt 23 against the inner surface of the standard 12, and the parts will be securely held. The standard 12 may be readily adjusted with respect to the base 10 by loosening the lower clamp and turning the said standard with respect thereto, whereupon the clamp may be again tightened. 10 While in Fig. 2 two positions for the lamp and standard respectively are shown; it is obvious that these parts may be caused to assume a great variety of positions with respect to each other and to the base 10. 15 Various modifications of the device hereinbefore described will readily suggest themselves to those skilled in the art and are to be considered as coming within the scope of my invention, which is set forth in the 20 following claims.

What I claim as new and desire to secure by Letters Patent of the United States, is:—

1. A lamp fixture comprising a standard having a slot therein, a bolt passing through 25 the said slot and carrying at one end a lamp socket supporting means and at its other end means for engaging the inner surface of said standard, and clamping means comprising a member carried by said bolt and engaging 30 the outer surface of said standard and means for causing said member to bear tightly against said standard or to be released therefrom as desired.

2. A lamp fixture comprising a standard 35 having a slot therein, a tubular bolt passing through said slot and having at one end thereof a lamp socket supporting means and at the other means engaging the inner surface of the said standard, means carried by 40 the said bolt and engaging the outer surface of said standard and means for clamping the said engaging means or releasing the same from engagement with said standard.

3. A lamp fixture comprising a standard 45 having a slot therein, a bolt passing through the said slot and having at one end thereof

lamp socket supporting means and at the other a head adapted to engage the inner surface of said standard, means carried by said bolt and engaging the outer surface of the said standard and means for clamping said head to said standard or releasing it therefrom as desired. 50

4. In a lamp fixture the combination of a standard having a slot therein, an externally threaded bolt passing through said slot and having a head engaging the inner surface of said standard, a bearing plate loosely carried on the said bolt and engaging the outer surface of the said standard, and an internally threaded member engaging a thread on said bolt and adapted to engage the said plate to clamp the aforesaid head against the said standard. 55

5. In a lamp fixture the combination of a standard having a slot therein, an externally threaded bolt passing through said slot and having a head engaging the inner surface of said standard, a bearing plate loosely carried on the said bolt and having a projection 70 engaging the said slot and engaging the outer surface of the said standard, and an internally threaded member engaging the thread on said bolt and adapted to be tightened against the said plate to clamp the 75 aforesaid head against the said standard.

6. In a lamp fixture the combination of a standard having a slot therein, an externally threaded bolt passing through said slot and having a head engaging the inner surface 80 of said standard, a bearing plate loosely carried on the said bolt and engaging the outer surface of the said standard, and an internally threaded winged member engaging the thread on said bolt and adapted to be 85 tightened against the said plate to clamp the aforesaid head against the said standard.

In witness whereof, I have hereunto set my hand this eighteenth day of August, 1915.

HENRY R. HUBERICH.
